(57) **CLAIM**

The ornamental design for a container for food, as shown.

DESCRIPTION

FIG. 1 is a front perspective view of a container for food showing our new design;

FIG. 2 is a top plan view thereof;

FIG. 3 is a bottom plan view thereof;

FIG. 4 is a front elevational view thereof;

FIG. 5; is a rear elevational view thereof;

FIG. 6 is a left side elevational view thereof; and,

FIG. 7 is a right side elevational view thereof.

The broken lines shown in the drawings are for illustrating portions of the container for food that form no part of the claimed design.
